UNITED STATES PATENT OFFICE

114,632

DESIGN FOR AN AUTOMOBILE RADIO SET

Gordon G. Brittan, Hubbard Woods, Ill., assignor to Warwick Manufacturing Corporation, Chicago, Ill., a corporation of Delaware

Application July 5, 1938, Serial No. 78,261

Term of patent 3½ years

To all whom it may concern:

Be it known that I, Gordon G. Brittan, a citizen of the United States, residing at Hubbard Woods, in the county of Cook and State of Illinois, have invented a new, original, and ornamental Design for an Automobile Radio Set, of which the following is a specification, reference being had to the accompanying drawing, forming part thereof.

In the drawing:

Fig. 1 is a front elevation of an automobile radio set showing my new design.

Fig. 2 is a side elevation of the automobile radio set shown in Fig. 1.

The dominant features of my design are shown in solid black lines in the drawing.

I claim:

The ornamental design for an automobile radio set, as shown and described.

GORDON G. BRITTAN.
